TUBULAR STOCK FOR USE IN CONSTRUCTING CHILDREN'S PLAY EQUIPMENT

Robert E. Feigenbaum, Carbondale, Ill., assignor to Turco
Manufacturing Company, Du Quoin, Ill., a corporation
of Missouri

Filed Jan. 7, 1963, Ser. No. 73,061

Term of patent 14 years

(Cl. D54—4)

FIG. 2

FIG. 4

FIG. 1

FIG. 5

FIG. 3

FIG. 1 is a front elevational view of a tubular stock for use in constructing children's play equipment embodying my new design;

FIG. 2 is a side elevational view thereof (as viewed from the right side of FIG. 1);

FIG. 3 is a side elevational view thereof (as viewed from the left side of FIG. 1); and

FIGS. 4 and 5 are sectional views taken along lines 4—4 and 5—5 of FIG. 1.

I claim:

The ornamental design for a tubular stock for use in

constructing children's play equipment, substantially as shown.
